(57) **CLAIM**

The ornamental design for a tool case, as shown and described.

DESCRIPTION

FIG. 1 is a front perspective view of the tool case of the present invention in a closed position showing my new design;

FIG. 2 is a perspective view of the tool case in an opened position;

FIG. 3 is a front side elevational view thereof;

FIG. 4 is a side elevational view thereof;

FIG. 5 is a back side elevational view thereof;

FIG. 6 is another side elevational view thereof;

FIG. 7 is a top plan view thereof;

FIG. 8 is a bottom plan view thereof;

FIG. 9 is another perspective view of the tool case in a closed position; and,

FIG. 10 is another perspective view of the tool case in an opened position.

The broken lines in the drawings illustrate aspects of the design that form no part of the claim.
